UNITED STATES PATENT OFFICE.

PAUL E. DOUGLASS, OF FLINT, MICHIGAN.

BENCH-DRILL.

1,254,485.

Specification of Letters Patent. Patented Jan. 22, 1918.

Application filed January 11, 1917. Serial No. 141,853.

To all whom it may concern:

Be it known that I, PAUL E. DOUGLASS, a citizen of the United States, residing at Flint, in the county of Genesee and State of Michigan, have invented certain new and useful Improvements in Bench-Drills, of which the following is a specification.

This invention relates to bench drills, and more particularly to a power driven drill 10 adapted to be mounted on a bench in the usual manner.

One of the main objects of the invention is to provide a drill of the character stated of simple construction and operation in 15 which the pressure exerted on the drill proper is at all times under direct control of the operator. A further object is to provide a drill in which the driving power may be quickly and easily controlled, the controlling means for the power being mounted on the lever for controlling the pressure exerted on the drill. Further objects will appear from the detailed description.

In the drawings:

25 Figure 1 is a side perspective view of the drill,

Fig. 2 is a side view taken from the side opposite to Fig. 1,

Fig. 3 is a fragmentary vertical sectional 30 view through the drive gearing, and

Fig. 4 is a fragmentary vertical sectional view through the mounting for the drill spindle.

The standard 1 is provided with an inwardly extending foot 2 and a head 3 carried by a hand screw 4 operative through an arm 5 mounted in spaced relation to the foot 2. This provides means whereby the standard may be secured to a bench or table. The 40 standard is further provided with an outwardly extending arm 6 which carries the usual disk-like table 7. Three spaced arms 8, 9, and 10 are provided at the upper portion of the standard, these arms being in 45 vertical alignment and positioned above the table 7. The arms 8, 9, and 10 are provided at their outer ends with integral collars 11, 12 and 13, respectively.

A drill spindle 14 is slidably mounted 50 through the collars 11, 12 and 13, and is provided at its lower end with a chuck 15 adapted to hold a drill 16 of any suitable type. The upper end portion of spindle 14 extends into a sleeve 17 in which it is rotatably held by a screw 18 threaded through the sleeve and engaging with an annular groove

19 in the spindle. The sleeve 17 is provided, at its upper end, with two integral spaced ears 20. A lug 21 formed integral with a hand lever 22 is pivotally secured through 60 these ears by a screw 23, the under surface of this lug being of arcuate shape so as to permit movement of the hand lever about the screw 23. The inner end of lever 22 is pivotally secured, as at 24, to the upper 65 end of a link 25 the lower end of which is pivoted to a lug 26 integral with the standard 1. A coil spring 27 is mounted about the drill spindle 14 and is confined between the collar 13 and the lower end of sleeve 17. 70 This spring acts by expansion to normally hold the drill spindle in raised position, as in Fig. 1 of the drawing. By grasping the handle 28 of lever 22 and pressing down on the same, the drill spindle, and consequently 75 the drill 16, will be forced downward toward the plate 7 so as to bring the drill into engagement with the work on the table. By varying the pressure on the lever the pressure on the drill may be varied as desired. 80 A bearing ball 29 is interposed between the inner end of sleeve 17 and the upper end of the drill spindle so as to reduce friction to a minimum.

A motor 30 is secured to the arm 10 of 85 standard 1 and extends at right angles thereto. The casing of this motor is provided with an upper arm 31 and a lower arm 32. The arm 32 has a forwardly extending stud 33 on which is rotatably mounted the drive 90 gear 34. This gear is provided, at its center, with a concentric drive gear 35 of considerably less diameter than gear 34, a suitable gear shifting mechanism, indicated generally by 36, being provided for operatively 95 connecting the drill spindle 14 to either one of the gears 34 or 35, thus providing a two speed drive. The gear 34 is provided with an integral internal gear 34^a. This internal gear meshes with a pinion 37 keyed on the 100 armature shaft 38 of motor 30. This motor is adapted to be connected up to a suitable source of electrical energy by means of the wires 39 and 40 which are passed through the motor casing. A push button 105 switch 41 is mounted in the outer end of handle 28 of lever 22, and is connected in series in the circuit of the motor by means of the leads 42 and 43. By operating the switch 41 the current of the motor may be 110 cut off as desired, thus providing simple means for controlling the motor, this means

being mounted in the handle for controlling the pressure exerted on the drill. By constructing the drill in this manner, and mounting the control switch for the motor 5 in the hand lever, the pressure exerted on the drill, and the operation of the drill, may be controlled with one hand, thus leaving the other hand free to shift the work on table 7 as may be necessary.

10 It will be evident that there may be slight changes made in the construction and arrangement of the different parts of my invention without departing from the field and scope of the same, and I intend to include all such variations, as fall within the scope of the appended claims, in this application in which a preferred form only of my invention is disclosed.

What I claim is:

20 1. In a bench drill, the combination of a standard, a table carried thereby, a rotatably mounted drill spindle carried by the standard and movable toward and away from the table, a hand lever pivotally connected to the standard, a sleeve pivotally secured to the lever and extending about the upper end portion of the drill spindle, an expansion spring mounted about the spindle below the sleeve so as to normally hold the sleeve in 30 raised position, and means for rotating the drill spindle.

2. In a bench drill, the combination of a standard provided with a plurality of spaced arms, a table carried by the standard beneath said arms, a spindle rotatably mounted in the arms and movable toward and away from the table, a hand lever pivotally connected to the standard, a sleeve pivotally secured to the hand lever and extending about the upper end portion of the spindle, means for rotatably securing the spindle in said sleeve, a coil spring mounted about the spindle and confined between the sleeve and one of the said arms, means for 40 rotating the spindle, and means carried by the hand lever for controlling the operation of the said rotating means.

3. In a bench drill, the combination of a standard provided with a plurality of spaced parallel arms, a table carried by the standard beneath said arms, a drill spindle rotatably mounted in the arms and movable toward and away from the table, a hand lever, a link pivotally secured at one end to the hand lever and at the other end to the standard, a sleeve carried by the hand lever and pivotally secured thereto, said sleeve extending downward about the upper end portion of the drill spindle, means for rotatably securing the drill spindle in the sleeve, an electric motor carried by the standard, driving connections between the motor and the drill spindle, and a control switch carried by the hand lever and interposed in the circuit of said motor.

4. In a bench drill, the combination of a standard provided with a plurality of spaced parallel arms, a table carried by the standard beneath said arms, a drill spindle rotatably mounted in the arms and movable toward and away from the table, a hand lever, a link pivotally secured at one end to the hand lever and at the other end to the standard, a sleeve carried by the hand lever and pivotally secured thereto, said sleeve extending downward about the upper end portion of the drill spindle, means for rotatably securing the drill spindle in the sleeve, an electric motor carried by the standard, driving connections between the motor and the drill spindle, a control switch carried by the hand lever and interposed in the circuit of said motor, and a coil spring mounted about the drill spindle and confined between the top-most arm carried by the standard and the sleeve adapted to normally hold the drill spindle in raised position.

In testimony whereof I affix my signature in presence of two witnesses.

PAUL E. DOUGLASS.
